UNITED STATES PATENT OFFICE

IRA L. FOSTER, OF FORT DODGE, IOWA

GRAVE-VAULT STRUCTURE

Application filed November 26, 1928. Serial No. 321,954.

The object of my invention is to provide a grave vault structure of simple, durable and comparatively inexpensive construction.

The primary object of my invention is to provide a vault structure in which electrolysis will not occur. In metal vaults, the vault itself is usually made of one metal and the casket on the inside thereof is made of another and more expensive metal. Due to the dissimilarity of these metals, they produce electrolysis of the casket itself, the vault structure or the body within the casket, depending on what metals are used in their construction and when the casket is placed in contact with the vault structure so that an electric circuit can be established between the two.

Electrolysis is a decomposition of the vault structure, the casket or the body within the casket caused by an electric current generated within the vault structure due to the dissimilarity of the metals used in the vault structure construction and the casket construction when the two are in contact with each other.

It has therefore, been my object to provide a means of insulation between the vault structure and the casket so that the chance of an electric circuit being established, is eliminated and consequently electrolysis cannot occur.

Still a further object is to provide in an air sealed type of vault structure, a vault bottom entirely arranged in a single plane instead of a portion thereof being upstruck for forming risers upon which the casket may rest. The purpose of this construction is so that the vault structure may easily be rolled over the rollers in the floor of a hearse which are usually shorter than the width of the vault bottom.

Still a further object is to provide a novel means for latching the vault bell or cover to the vault bottom.

With these and other objects in view my invention consists in the construction, arrangement and combination of the various parts of my device, whereby the objects contemplated are attained, as hereinafter more fully set forth, pointed out in my claims, and

illustrated in the accompanying drawings, in which:—

Figure 1 is a longitudinal vertical sectional view through a vault structure, embodying my invention and illustrating a casket therein in side elevation.

Figure 2 is an enlarged sectional view on the line 2—2 of Figure 1.

Figure 3 is a sectional view of a portion of Figure 2, illustrating the latch in a different position.

Figure 4 is a sectional view on the line 4—4 of Figure 2; and

Figure 5 is a perspective view of one of the risers of my device illustrating the insulating means applied thereto.

In the accompanying drawings, I have used the reference numeral 10 to indicate a vault bottom of flat sheet metal construction. The sides and ends thereof are upturned slightly as indicated at 12. A vault bell or cover 14 coacts with the bottom 10 and is provided with an inturned and upturned peripheral flange 16.

Secured to the bottom member 10, are a plurality of risers A consisting of side plates 18 having feet 20 formed thereon. The feet 20 may be riveted or welded to the bottom 10. The side members 18 of the risers A are provided with flanges 22. At each end of each riser A, gravity locks 24 are provided. The locks 24 are pivoted to the side flanges 18 by means of rivets or the like 26. Each lock 24 is provided with a catch shoulder 28 and a stop lug 30.

Openings 32 are provided in the side plates 18 to receive cotter keys 34 as illustrated in Figure 3 of the drawings for the purpose of rendering the locks inoperative when shipping the vault structure.

An insulating member 36 is provided on each riser A and may be secured thereto in any suitable manner such as by rivets 38 or the like extending through a downwardly projecting rib 37 on the member. The member may be held by clamps of friction also. The insulator 36 may be of wood, glass, cork, rubber, fiber, bakelite or any other suitable insulating material and is provided for resting the casket 40 on and prevents its contact

with the risers A or the bottom 10 of the vault structure.

It is the general practice to buy quite an expensive casket such as one made of bronze, zinc, copper, Armco iron or Keystone steel. This list of course, does not include wooden caskets since electrolysis does not occur when they are used due to the fact that they are of insulating material themselves. One way of effectively preventing electrolysis, is to purchase the metal vault at bottom 10, bell 14 and casket 40 all of similar metal, but this increases the expense greatly. Therefore, cheaper vault structures are used for the purpose of making a water seal vault and by using any number of the risers A capped with the insulating bars 36, a metal casket made of a metal dissimilar from that from which the vault structure is made, may be placed within the vault structure without the danger of electrolysis occurring which of course, is a very deplorable result when using vault structures and caskets of dissimilar metals without insulation between them.

In air seal vaults of the bell type, water rises about an inch or so above the lower end of the bell. To prevent this water from coming in contact with the casket, vault bottoms are usually pressed upwardly for raising the bottom of the casket above the lower edge of the bell. In my construction the vault bottom is made flat and the riser members 18 serve the purpose of raising the casket while at the same time they serve as a convenient way of supporting the bars 36 of insulation.

By the use of gravity locks 24, the danger of springs rusting out as in the types of locks now in general use is eliminated.

Considerable changes in the construction of the risers and the locks 24 as well as in the vault structure itself, may be made without departing from the real spirit and purpose of my invention in which a means of insulation is provided between the casket and the vault structure.

It is therefore, my purpose to cover by my claim, such modifications in the form of the structure and use of mechanical equivalents as may be construed as falling within their scope.

I claim as my invention:

In a metal grave vault structure, a vault bottom member, a vault cover member for coaction therewith and a riser member on said bottom member, said riser member being adapted for having a casket made of a metal different from the grave vault structure supported thereon, said riser member being capped with an insulating material whereby to prevent the occurrence of electrolysis of a body within said casket.

IRAL FOSTER.
